UNITED STATES PATENT OFFICE.

MATTHIAS BROCK, OF BOSTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

METHOD OF PREPARING SHOE-UPPERS.

1,285,011.

Specification of Letters Patent.

Patented Nov. 19, 1918.

Application filed July 29, 1916, Serial No. 112,108. Renewed April 16, 1918. Serial No. 228,971.

To all whom it may concern:

Be it known that I, MATTHIAS BROCK, a citizen of the United States, residing at Boston, in the county of Suffolk and State 5 of Massachusetts, have invented certain Improvements in Methods of Preparing Shoe-Uppers, of which the following description, in connection with the accompanying drawings, is a specification, like reference characters 10 on the drawings indicating like parts in the several figures.

This invention relates to the manufacture of boots and shoes and more particularly to the preparation of a boot or shoe upper for 15 incorporation into a shoe.

In the manufacture of boots and shoes according to one method which is being extensively used, the assembled upper materials at the toe or heel portions of the upper, or it may be at both portions, including 20 the toe and heel stiffeners, are molded preliminarily to assembling the upper on the last into the shape desired for these parts in the finished shoe. Although the molding 25 operation gives a substantial permanency of shape to the upper materials at these points the uppers are frequently subject to considerable handling before they are incorporated 30 in the shoes and they often remain stacked in large quantities for some time before being used. These conditions tend to 35 destroy the shape originally imparted to the upper in the molding operation and also allow a reaction of the upper materials particularly when the uppers are exposed to dampness.

The present invention has for its principal object to provide a method of preparing shoe uppers for incorporation into a shoe by 40 the practice of which the molded conformed portion of the shoe upper may be treated in such manner as to prevent the molded upper materials from being distorted from the shape originally imparted to them before 45 the upper is assembled on the last upon which the shoe is to be made.

As herein shown the desired results are accomplished by providing a connecting strip of a length to extend between the opposite sides of the conformed portion of the shoe upper and securing the ends of this connecting strip to the marginal edges of the upper materials at opposite sides of the shoe upper. By reason of this strip the con-

formed portion of the shoe upper is held 55 against spreading out and the upper materials are prevented from returning to their normal condition after being released from shaping pressure. Furthermore, this method of preparing a shoe upper greatly facilitates 60 the accurate assembling of the upper on the last and, when applied to the heel portion of the upper, aids considerably in properly positioning and holding the upper on the last during the lasting operations performed on 65 the toe and side portions of the shoe.

As herein shown the connecting strip is applied only to the assembled heel portion of the shoe upper and preferably it is secured at either end to an inturned heel seat flange 70 at the forward ends of the heel stiffener. In order properly to position and to secure the connecting strip to the shoe upper the strip is preferably secured at either end while the heel portion of the upper materials 75 including the heel stiffener are conformed about the heel form or before the shoe upper is released from the molding pressure. The illustrated mechanism for applying this strip comprises a heel form about which the upper materials are shaped and which is 80 equipped with means arranged to insert tacks from the inside up through the in-turned heel seat flange of the upper and the connecting strip after the upper materials 85 have been conformed about the inside former. The inside former may be provided with means adapted to hold the connecting strip in position for the lower marginal portion of the upper materials to be folded over 90 the ends of the strip during the shaping of the upper materials to insure the proper attachment of the connecting strip to the heel seat flange to maintain the conformed condition of the upper after it is released from 95 molding pressure.

Other objects and features of the present invention will be apparent from the following description when considered in connection with the accompanying drawings which 100 illustrate a preferred method by which the invention may be practiced and the novel features are set forth in the appended claims.

In the drawings,—
Figure 1 shows a shoe upper in position 105 to be operated upon by the upper shaping mechanism of a machine which I have em-

ployed to advantage in practising my invention; and

Fig. 2 shows the heel portion of a shoe upper after its treatment in accordance with 5 the method of this invention.

The general organization of the machine, partly illustrated herein, in conjunction with the method of the present invention is fully shown and described in U. S. Letters 10 Patent No. 1,197,437, granted September 5, 1916, on my application Serial No. 728,183 filed Oct. 28, 1912, of which this application is a continuation as to disclosure of subject-matter which is common to the two applications.

The illustrated shoe upper comprises a leather upper 2 with its lining 4 and a heel stiffener 6 which may be of leather or other fibrous material capable of being conformed 20 to the desired shape. These parts, after being properly assembled, are placed between a last-like form or mold 8 having the general shape of the heel portion of a last and a co-operating outer form or mold 10, as illustrated in Fig. 1.

As more fully shown and described in my co-pending application the inner form 8 is mounted upon a jack post 12 which is yieldingly supported by a jack supporting post 20 having connections to operating mechanism to move the inner form with the assembled upper thereon rearwardly to carry the form 8 into the outer mold 10 and also to elevate the jack. The outer form or mold 10 comprises a plurality of relatively movable jaws the inner faces of which correspond to the contour of the side faces of the inner form 8 and are preferably covered by a lining of hard leather 14 which gives continuity to the 35 shaping surface of the outer form. In the illustrated method of preparing shoe uppers the heel portion of the upper is provided with an inturned heel seat flange 15 which is formed by means comprising a plurality of wiper plates 16 which, when in their normal or retracted positions, project forwardly beyond the shaping surface of the outer mold so that as the work is forced back into the 40 outer mold 10 the lower marginal portion of the upper materials is turned inwardly onto the upper surface 18 of the inner form 8.

The surface 18 of the inner form 8 is preferably provided with two projecting pins 20 located near the forward edge of the heel form and upon which a connecting strip 22 is pressed to hold the strip in position during the shaping of the upper materials about the heel form 8. This connecting strip may conveniently be formed of a substantially narrow strip of fabric or other inelastic material and is of sufficient length to bridge the shoe upper from the heel seat flange 15 at one side of the upper to the opposite portion 55 of the flange and preferably at the forward

ends of the heel stiffener 6 or near the termination of the conformed portion of the shoe upper.

Conveniently the connecting strip 22 is placed in position on the pins 20 at the time 70 the assembled upper is placed in position to be conformed so that as the heel form with the shoe upper thereon is moved rearwardly into the outer form 10 the lower marginal portion of the upper materials overlying the 75 ends of the strip is wiped in over the ends of the connecting strip.

In order to secure the ends of the connecting strip 22 to the inturned heel seat flange 80 15 the heel form 8 is provided with tack drivers 26 which are arranged to insert tacks 27 from the inside up through the ends of the connecting strip and the inturned margin of the upper materials. These tack drivers are advantageously located at the forward corners of the heel form 8 and owing to the difficulties in the use of the ordinary driver due to the shape of the heel form at these points, a plurality of balls 28 are utilized to transmit tack driving movement between the tack drivers 26 and driver operating bars 30 which are secured at their lower ends to the jack supporting post. In the normal inoperative position of the drivers 26 in the driver passages the tacks 27 which are to be driven are placed by hand in the driver passages preferably before the shaping operation upon the upper materials has been completed. The tack drivers 26 may also be positioned in the driver passages so that when the tacks 27 are placed in the driver passages the points of the tacks will project above the surface 18 of the heel form 8 and provide means to hold the connecting strip 22 in position on the heel form.

In the practice of the invention in conjunction with the machine of said co-pending application above mentioned, the assembled heel portion of the shoe upper after having been properly positioned and tensioned about the heel form 8 is drawn back into the outer form 10 by the rearward movement of the heel form 8 and the upper materials are then placed under conforming or shaping pressure by the closing of the outer form 10 about the heel form 8. The relative movements of the inner and outer forms 8 and 10, respectively, and the elevation of the jack post carrying the heel form cause an initial turning-in of the marginal portions of the upper materials over the heel seat face 18 of the inner form 8 and the ends of the connecting strip 22 by the overhanging portions of the wiper plates 16. The wiper plates 16 may then be reciprocated repeatedly and in timed relation to the intermittent elevation of the jack post and heel form to shape and conform the upper materials to the contour of the inner and outer forms and

to form the inturned heel seat flange 17. After the upper materials have received the desired amount of shaping and conforming treatment and preferably while the upper materials are still under shaping pressure between the inner and outer forms the tacks 27 in the driver passages are driven up through the ends of the connecting strip 22 and the inturned heel seat flange 17 of the upper by the elevation of the jack post, the tacks being clenched on the under side of the overhanging portions of the wipers 16.

When the shoe upper is removed from the machine the treated heel portion of the upper is maintained against spreading out and the upper materials are prevented from returning to their normal conditions regardless of when the shoe uppers are incorporated in the shoe.

When the prepared shoe upper illustrated in Fig. 2 is applied to the last upon which the shoe is to be made the heel portion fits snugly about the heel end of the last in accurate position and provides a pocket to receive the heel end of the last so as to prevent shifting or displacement of the upper on the last during succeeding operations on the shoe. Also the shoe uppers prepared in accordance with the method of the present invention are not distorted or injured by the more or less severe handling to which they are subject and the several parts of the shoe upper cannot become separated and lost during such handling.

Although the invention has been herein illustrated and described in conjunction with a machine for preliminarily conforming the heel portion of an upper prior to assembling the upper on a last it is to be understood that the invention may also be employed to advantage in preparing a shoe upper in which the upper materials at the heel end of the shoe upper are not preliminarily shaped before applying a connecting strip.

Having thus described my invention, what I claim as new and desire to secure by Letters Patent of the United States is:

1. That improvement in methods of preparing a shoe upper for incorporation into a shoe which consists in assembling the upper materials, including an upper stiffener, and, before applying the upper materials to the last upon which the shoe is to be made, connecting opposite sides of one end of the assembled upper materials at their marginal edges by a connecting strip of a length to bridge across the end portion of the upper when the upper is in approximately the shape it is to take in the finished shoe.

2. That improvement in methods of preparing a shoe upper for incorporation into a shoe which consists in assembling the upper materials including an upper stiffener,

and, before applying the upper materials to the last on which the shoe is to be made, connecting the marginal edges of the opposite sides of the upper materials at one end of the upper by a bridge member of a length to maintain said end portion of the upper in approximately the relative position the opposite sides of the upper materials occupy when assembled on the last.

3. That improvement in methods of preparing a shoe upper for incorporation into a shoe which consists in conforming the upper materials of an end of the shoe including an upper stiffener to the shape of these parts in the finished shoe and securing a connecting strip to the lower marginal edges of opposite sides of the shaped portion of the upper to maintain the shaped condition of the upper materials, all prior to assembling the upper materials on the last upon which the shoe is to be made.

4. That improvement in methods of making shoes which consists in conforming the upper materials of an end of the shoe including an upper stiffener to the shape of these parts in the finished shoe and connecting the lower marginal edges of the shaped portion of the upper materials by a connecting strip of a length to maintain the conformed condition of the upper materials, and thereafter assembling the prepared upper on a last and proceeding with the making of the shoe.

5. That improvement in methods of making shoes which consists in preliminarily molding an end portion of a shoe upper off the last to the shape of these parts in a finished shoe and connecting the sides of the molded end portion to maintain the upper against spreading before releasing the upper materials from molding pressure, and subsequently applying the preliminarily molded upper to a last and then proceeding with the making of the shoe.

6. That improvement in methods of making shoes which consists in preliminarily molding the upper materials of a portion of the shoe including an upper stiffener off the last to substantially the shape these parts are to have in the finished shoe and connecting the lower marginal portions of opposite sides of the shaped portion of the upper materials by a connecting strip to assist in retaining the molded shape of the upper during subsequent operations on the shoe.

7. That improvement in methods of making shoes which consists in applying a heel stiffener to the upper materials, shaping the upper materials including the heel stiffener over a heel mold other than the last upon which the shoe is to be made to the approximate shape of these parts in the finished shoe and connecting the lower mar-

ginal edges of opposite sides of the upper materials at the forward ends of the heel stiffener by a connecting strip of a length to maintain the ends of the heel stiffener in the relative positions they are to occupy in the finished shoe, removing the shaped upper from the heel form and subsequently applying the upper to the last upon which the shoe is to be made.

10. 8. That improvement in methods of making shoes which consists in conforming the heel portion of the shoe upper including a heel stiffener to the shape of a heel form other than the last upon which the shoe is to be made and turning a heel seat flange inwardly over the heel form, and connecting opposite portions of the heel seat flange at the forward ends of the heel stiffener by a flexible connecting strip of a length to hold the heel portion of the upper from spreading, removing the upper from the heel form and subsequently assembling the upper on the last.

9. That improvement in methods of preparing a shoe upper for incorporation into a shoe before applying the upper to the last upon which the shoe is to be made which consists in molding the heel portion of the shoe upper including a heel stiffener by pressure to the shape of a heel form and turning a heel seat flange inwardly over the heel form, providing a flexible connecting strip of a length to join opposite portions of the heel seat flange at the forward ends of the heel stiffener, and then securing the ends of said connecting strip to the heel seat flange at the forward ends of the heel stiffener before the upper materials have been released from molding pressure about the heel form.

40. 10. That improvement in methods of preparing a shoe upper for incorporation in a shoe which consists in providing a form having a shape corresponding to the heel end of a last, assembling thereon the upper materials including a heel stiffener, conforming the heel portion of the upper to the shape of said heel form and turning a heel seat flange inwardly over the top face of the heel form, applying a connecting strip to the heel form, said strip being of substantially the same length as the width of the heel form at its forward edge, and then inserting fastenings through the ends of the connecting strip and the heel seat flange while the upper materials are conformed about the heel form.

11. A shoe upper prepared prior to its application to the last upon which the shoe is to be made with its end portion stiffened and the lower marginal edges of its opposite sides at the stiffened portion connected by an inelastic connecting strip of a length to

maintain the opposite sides of the end portion of the upper in the relative positions they occupy when assembled on the last.

12. A shoe upper with its end portion conformed approximately to the shape of these parts in the finished shoe preparatory to applying the upper to the last upon which the shoe is to be made and having the lower marginal edges of the opposite sides of its shaped portion connected by an inelastic connecting strip to maintain the shaped portion of the upper from spreading.

13. A shoe upper with its heel portion including a heel stiffener conformed to the shape of these parts in the finished shoe preparatory to applying the upper to the last upon which the shoe is to be made and having the lower marginal edges of its opposite sides at the forward ends of the heel stiffener connected by an inelastic connecting strip in the conformed condition of the upper materials to hold the heel portion of the upper from spreading.

14. A shoe upper with its heel portion including a heel stiffener conformed to the shape of these parts in the finished shoe preparatory to applying the upper to the last upon which the shoe is to be made and having a heel seat flange extending at substantially right angles to the adjacent body portion of the upper and having a flexible connecting strip extending across the upper at the forward ends of the heel stiffener and secured at its ends to the heel seat flange to maintain the upper against spreading.

15. A shoe upper with its heel portion including a heel stiffener conformed to the shape of these parts in the finished shoe preparatory to applying the upper to the last upon which the shoe is to be made and having a heel seat flange extending at substantially right angles to the adjacent body portion of the upper and maintained in said shaped condition by an inelastic connecting strip joining opposite portions of the heel seat flange at the forward ends of the heel stiffener.

16. A shoe upper with its heel portion including a heel stiffener conformed to the shape of these parts in the finished shoe preparatory to applying the upper to the last upon which the shoe is to be made and having an inturned heel seat flange and having an inelastic connecting strip of a length to join opposite portions of the heel seat flange at the forward ends of the heel stiffener and secured at its ends to said inturned heel seat flange.

In testimony whereof I have signed my name to this specification.

MATTHIAS BROCK.
